APPARATUS FOR DRYING SHORT ALIMENTARY PASTE

Nicholas J. Cavagnaro, Richmond Hill, N. Y., assignor to Consolidated Macaroni Machinery Corporation, Brooklyn, N. Y., a corporation of New York

Application January 29, 1935, Serial No. 3,925

4 Claims. (CL 34—12)

This invention relates to improvements in method and apparatus for drying short cut alimentary paste, and also for drying egg noodles and similar paste products.

5 The invention has for its principal object to provide a novel method of drying paste products, and especially for drying egg noodles, whereby not only is checking or souring of the product avoided, but its color is maintained against 10 bleaching during the drying treatment.

The invention has for a further object to provide a novel apparatus by which the various drying steps may be automatically carried out, i. e. preliminary drying, annealing, and final drying 15 steps are automatically and successively applied to the product under the most sanitary and efficient conditions, so that during the processes the product is untouched by human hands, and is finally delivered in finished state free from dust 20 and ready for immediate packing. The novel apparatus, according to this invention, is designed for continuous operation, subject to full control of desired conditions attendant upon each treatment step.

25 Other objects of this invention, not at this time more particularly enumerated, will be understood from the following detailed description of the same.

Illustrative embodiments of the invention are 30 shown in the accompanying drawings, in which:-

Fig. 1 is a side elevation of the novel drier apparatus per se and as adapted to carry on the novel method of treatment according to this invention; Fig. 2 is a longitudinal vertical section 35 through the apparatus; and Fig. 3 is a transverse vertical section of the same, taken on line 3—3 in Fig. 2. Fig. 4 is a fragmentary horizontal section, taken on line 4—4 in Fig. 2. Fig. 5 is a schematic view showing a modified arrangement of the apparatus.

Similar characters of reference are employed in the above described views, to indicate corresponding parts.

Referring to the drawings, one form of the 45 novel drying apparatus, as shown in Figs. 1, 2, and 3, comprises a cabinet or housing 6, the interior of which is horizontally divided, by partitions 7 and 8, to form therein an upper preliminary drying chamber 9, an intermediate annealing chamber 10 and a lower final drying chamber 11. Extending longitudinally within the preliminary drying chamber 9 are a plurality of horizontal endless conveyer aprons, preferably at 50 least two in number, viz. the upper apron 12 and 55 the lower apron 13, the latter being spaced below

the former. These aprons are supported at their ends by rollers 14, one for each said apron being a driving roller. These rollers are fixed upon transverse shafts 15, the shafts of the driving rollers being driven by suitable power transmission means, an illustrative arrangement of which will be subsequently described. These aprons are relatively arranged so that the discharge end of the upper apron 12 overhangs and discharges upon the receiving end of the lower apron 13; 10 these aprons running in opposite directions, e. g. the upper apron 12 running from left to right and the lower apron from right to left. The aprons 12 and 13 are made of wire mesh fabric so as to allow air to unobstructedly pass therethrough. 15 Arranged at the top of the cabinet or housing 6, above the receiving end of the upper apron 12, is a means for delivering the material to be treated into the preliminary drying chamber 9 and onto the receiving end of the upper apron 12. 20 This means comprises a conduit 16, through which the material may be moved from a source of supply either by gravity or pneumatically. Connected with the inner end of said conduit 16 is a delivery nozzle or chute 17, which is arranged 25 to oscillate about a vertical axis, whereby its discharge end is laterally swung from side to side across the apron 12, thereby to spread out the delivered material upon and across the latter. Any suitable means may be provided for producing 30 the desired oscillatory movement of the delivery nozzle or chute 17. Illustrative of one such means, said nozzle or chute 17 is provided with a pivotally mounted bracket 18, adapted to turn on a pivotal support 18', and extending from 35 said bracket is a lever arm 19. A driver shaft 66, of the subsequently described power transmission means, is provided with a crank-portion 20, which is operatively connected to the lever arm 19 by a connecting rod 21.

Connected with one side of the cabinet or housing 6 is an air intake box 22, the interior of which provides an air chamber 23, and the wall of the cabinet or housing 6, intermediate the preliminary drying chamber 9 and said air chamber 23 is provided with one or more communication openings 24. In connection with said air intake box 22 is a hinged cover 25, which can be adjusted in more or less open condition to admit air from the atmosphere into said air intake box. Within said air chamber 23 is suitably mounted a source of heat for warming the air, the same preferably comprising a steam radiator 26. Mounted on transverse shafts 27 journaled in bearings 28 are air impeller fans 29, 50 55

which are respectively positioned at the communication openings 24 between the air chamber 23 and the interior of the preliminary drying chamber 9. Air exhaust ports 24', having suitable means for controlling the same, such as manipulatable doors 24'', are provided in the opposite side walls of the preliminary drying chamber 9, preferably at the lower portions of said chamber.

10 At the discharge end of the lower apron 13 is located a drop chute or hatchway 30 which extends through the partition to communicate with the interior of the annealing chamber 10. Extending longitudinally through the interior of 15 the annealing chamber 10 is a horizontal endless conveyer apron 31, the receiving end of which is disposed beneath the drop chute or hatchway 30, to extend therefrom through the annealing chamber to and through an exit opening 32 in 20 an end wall thereof. This conveyer apron 31, which runs from left to right, is preferably made of canvas or similar flexible sheet material, and the same is supported at its ends upon rollers 33, which are fixed upon transverse shafts 34, one 25 of which serves as a driving shaft. Arranged within said annealing chamber 10 is a steam discharge pipe 35, low pressure steam to which is supplied through a delivery pipe 36 from a suitable source; said delivery pipe 36 being furnished with a control valve 37, if desired.

Extending longitudinally within the final drying chamber 11 are a plurality of horizontal endless conveyer aprons, which may vary in number, four being shown by way of example, viz. 35 a first conveyer apron 38, a second conveyer apron 39, a third conveyer apron 40, and a fourth conveyer apron 41, spaced apart one below the other. These conveyer aprons are supported at their ends by rollers 42 fixed upon transverse 40 shafts 43, one roller for each apron being a driving roller the shafts of which are driven by a suitable power transmission means, such e. g. as that subsequently described. The receiving end of the first conveyer apron 38 is projected 45 outwardly through an intake opening 44 provided in an end wall of the final drying chamber 11, so as to be disposed beneath the discharge end of said conveyer apron 31 issuing from the annealing chamber 10. The receiving end of said 50 first conveyer apron 38 is surrounded by a hopper-like enclosure 45, and if desired a flexible guide member 46 is mounted within the hopper-like enclosure to control the deposit of material onto the first conveyer apron 38 as the 55 material drops from the conveyer apron 31 issuing from the annealing chamber 10. The several conveyer aprons 38, 39, 40, and 41 are preferably made of wire mesh fabric to allow the circulation of air therethrough, and the same are 60 relatively arranged so that the discharge end of one overhangs the receiving end of the next below; alternative conveyer aprons running in opposite directions; e. g. the first conveyer apron 38 runs from right to left, the second from left to right, the third again from right to left, and the fourth from left to right, with its discharge 65 end projected outwardly through a discharge opening 47 provided in an end wall of said final drying chamber 11. Receptacles 48, of suitable 70 character, may be placed beneath the projected discharge end of the last named conveyer apron, to receive the finished product as discharged therefrom. Provided in a side wall of the final drying chamber 11 is an air admission opening 75 49 provided with control door 50, which can be

adjusted in more or less open condition to admit air into the upper interior of said final drying chamber 11. Arranged within the upper interior of said final drying chamber 11 are a plurality of laterally spaced longitudinally extending baffles 51, preferably disposed at different levels, and adapted to deflect incoming air downwardly at different points for circulation through the chamber and the conveyer aprons therein for contact with the material 10 carried by the latter for treatment. Connected with the opposite side of said final drying chamber 11 is an enclosed air heating compartment 52, within which is suitably mounted a source of heat for warming air, the same preferably comprising a steam radiator 53. The previously described steam radiator 26 of the air intake box 22, as well as said radiator 53, may be supplied by steam delivery piping 54 leading from a suitable steam supply. The side 20 wall of the final drying chamber 11, adjacent to the air heating compartment 52 is provided with a plurality of spaced communication openings 55, leading from the lower end of said final drying chamber 11 into the lower end of said air heating compartment 52, and is further provided with a communication opening 56, leading from the upper end of said air heating compartment 52 into the upper interior of said final drying chamber 11. In the lower portion of the outer 25 wall of said air heating compartment 52 are air vent openings 57 having closure members 58 which can be adjusted in more or less open conditions to vent some of the air from said heating compartment 52 as occasion may require. Mounted on transverse shafts 59 journaled in bearings 60 are air impeller fans 61, which are respectively positioned at the communication openings 55 between the lower end of the final drying chamber 11 and the interior of the air heating compartment 52; these fans serving to drive the air admitted to the final drying chamber 11 through the air heating compartment 52 so that the same is warmed therein, and thereupon returned through the upper communication opening 56 30 for recirculation through the final drying chamber 11.

Any suitable arrangement for applying power for operation of the various conveyer aprons, air impeller fans, and other operable parts of the apparatus may be provided. Preferably a power source of the electric motor type is desirable, and the transmission means operated thereby is so designed on speed reduction principles as to operate the various conveyer aprons at predetermined relative speed ratios, whereby the travel of material under the various treatment steps although continuous, is nevertheless predetermined as to length of time required as to each step. Illustrative embodiments of power transmission means are shown in the drawings, the arrangement thereof being such that one motor 62 is provided to supply operating power to the conveyer aprons and fans of the preliminary drying section of the apparatus, and also to the conveyer apron of the annealing chamber section, while a separate motor 63 is provided to supply operating power to the conveyer aprons and fans of the final drying section of the apparatus. The motor 62 is preferably mounted on the top of the housing or cabinet 6, and transmits, through direct belt and pulley drives 64, comparatively high speed rotation to the driving shafts 27 of the air impeller fans 29. One of said driving shafts 27 is utilized to drive a series of transverse shafts 65, 70 75

66, and 67 through a speed reduction transmission, comprising a pulley 68 on shaft 65 driven by a belt and pulley drive 69 from a fan shaft 27, a chain and sprocket reduction drive 70 between said shafts 65 and 66, and a chain and sprocket reduction drive 71 between said shafts 66 and 67. The drive shafts 15 for the preliminary drying chamber conveyer aprons 12 and 13 are each provided with sprockets 72, and the drive shaft 34 for the annealing chamber conveyer apron 31 is provided with a properly sized sprocket 73. The said sprockets 72 and 73 are driven by a chain and sprocket drive 14 from the shaft 67. The motor 63 is mounted on the floor adjacent to the housing or cabinet 6, and transmits through interconnecting belt and pulley drives 75, comparatively high speed rotation to the driving shafts 59 of the air impeller fans 61. The motor 63 is also utilized to drive transverse shafts 76 and 77 through speed reduction transmission, comprising a pulley 78 on said shaft 76 driven by a belt and pulley drive 79 from the motor shaft, a pulley 80 on said shaft 77 driven by a belt and pulley drive 81 from said shaft 76. The drive shafts 43 for the final drying chamber conveyer aprons 38 to 41 inclusive are each provided with sprockets 82, which are driven by a chain and sprocket drive 83 from the shaft 77, the chain of said drive running over idler sprockets 84 mounted on transverse shafts 85, whereby a course of the chain may be alternately looped around the sprockets 82 to produce the opposite directional movements of alternate conveyer aprons 38 to 41 inclusive.

35 The novel method of drying, according to this invention, and as carried out by aid of the novel apparatus above described, consists in the following treatment. Assuming that the material to be dried is an egg noodle product. This product 40 possesses a characteristic yellow color, and it is highly desirable that this color be retained in the finished product, i. e. not alone is it necessary for the product to be thoroughly dried without checking or weakening of its structure, but tendency of the desired yellow color to bleach out 45 during the drying process should also be prevented. In treating an egg noodle product, the freshly formed noodle elements issuing from a cutter, or short paste products issuing from the 50 press are delivered, as e. g. through the conduit 16, to the delivery nozzle or chute 11. This nozzle or chute being oscillated from side to side over the receiving end of the first conveyer apron 12 in the preliminary drying chamber 9 of the 55 apparatus, effectively delivers the noodle elements upon said conveyer apron in spread out arrangement over and upon the surface thereof. By operation of the apparatus the conveyer apron 12 slowly carries the thus outspread noodle elements through the preliminary drying chamber 60 65 9, said noodle elements falling from the discharge end of the conveyer apron 12 onto the receiving end of the conveyer apron 13 so that the elements twice traverse the length of the preliminary drying member 9, and are consequently thus subjected to preliminary drying treatment over an adequate period of time. In the preliminary drying warm air is delivered by the impeller fans 29 from the air intake chamber 23 into and circulated 70 75 through the interior of the preliminary drying chamber 9 in contact with the noodle elements traveling therethrough, such air exhausting through the controllable ports 24. During this preliminary drying treatment the warm air currents tend to absorb and carry off moisture

nearest the surface of the noodle elements, leaving, however, a considerable amount of moisture within the internal parts or core of the paste dough. If such surface drying is continued too long, the surface of the paste dough is likely to 5 become hard and brittle, and would tend to check and crack with the consequent weakening of the noodle structure and ultimate spoiling of the same for commercial handling and distribution. Furthermore, the drying tends to bleach color 10 from the noodle dough, leaving the product pale and whitish, instead of possessing the bright yellow color so highly desirable in an egg noodle product. For these reasons, the preliminary drying must be terminated, both to arrest bleaching 15 action and to give time for the still residual moisture of the core parts of the noodle elements to work out to the surface. In a continuous treatment process, as here involved, the period of preliminary drying effect is determined by the speed 20 of travel of the conveyer aprons 12-13, and is automatically brought to a timely end with respect to the progressing portions of the noodle elements by discharge of the latter from the conveyer apron 13 through the drop chute or 25 hatchway 30 into the annealing chamber 10. The noodle material thus delivered into the annealing chamber 10 falls upon the receiving end of the slowly traveling conveyer apron 31, so as to be carried thereby through the interior of said 30 annealing chamber. In this chamber air circulation is substantially eliminated, but steam in suitably controlled amount is injected thereinto to permeate the still atmosphere thereof. This steam treatment is especially desirable in connection with an egg noodle product, since the moist warm atmosphere produced thereby tends to check all tendency of the product to bleach 35 and restores thereto the desired characteristic yellow color; while at the same time the warm 40 comparatively still air tempers the surface of the noodle elements against cracking or checking, while sufficient time is allowed, during the travel of the product through the annealing chamber, to allow the moisture from the center or core of 45 the paste dough to work outwardly to the surface portions thereof. The travel of the conveyer apron 31 is so timed that it will accommodate all the material discharged from the preliminary 50 drying chamber 9, and will at the same time move the received material at such speed through the annealing chamber as to assure attainment of the treatment effects above mentioned. At the end of the tempering and color restoring treatment, the noodle elements are discharged from the conveyer apron 31 onto the receiving end of the first 55 conveyer apron 38 of the final drying chamber 11. The aprons are so arranged that this transfer occurs exteriorly of the final drying chamber 11, so that direct communication between the interior of the steam filled annealing chamber 10 and the final drying chamber 11 is avoided, to the end that steam from the former cannot enter the latter and deleteriously effect the warm dry air which is circulated through the latter. 60 By the operation of the driving transmission the conveyer aprons 38 to 41 slowly carry the noodle elements back and forth through the final drying chamber 11. Here the noodle elements are subjected to a final drying step produced by the 65 circulation around and in contact therewith of currents of warm dry air. These air currents are induced by the action of the impeller fans 61, which drive the air taken in through the admission opening 49 into and through the air heat- 70 75

ing compartment 52, returning the warm air into the top of the interior of the final drying chamber 11 through the communication opening 56 for continued circulation in drying contact with the noodle elements. In order to assure the circulated air against too great saturation with moisture and to renew more or less the volume of dry air, the openings 57 may be opened, to such extent as best adapted to maintain desired conditions, so that some moist air may escape therethrough to be replaced by additional incoming air admitted through the opening 49. The effect of the dry warm air, as thus circulated in contact with the noodle elements traveling through the final drying chamber 11, is to gradually remove the remaining moisture from the paste dough, until, by the time the noodle elements are discharged through the passage 47 by the last conveyer apron 41, the same are thoroughly dried and hardened into that condition necessary to permit packing and commercial handling thereof.

From the above description it will be apparent that the noodle elements while continuously under uninterrupted movement through the apparatus, are nevertheless automatically subject to the required successive drying treatment steps, viz. preliminary drying, intermediate annealing and color restoration treatment, and then final drying. All this is accomplished automatically with a minimum necessity for attention, and without need for intervening human handling of the material. By reason of this the process is one which especially commends itself from sanitary standpoints and cleanliness, since handling of partially dried material, or exposure thereof to dusty or unclean surroundings is entirely eliminated.

While the method and apparatus involved is especially adapted to the drying of egg noodle products, it is also generally applicable to the drying of short cut paste products of various kinds; and in the latter connection the steam treatment may be omitted in the intermediate annealing step, and during this step submitting the product merely to dry and comparatively still air, so that moisture from the central parts or core of the cut paste elements may work out to the surface preparatory to final drying treatment.

The apparatus in the form shown in Figs. 1, 2, and 3 is arranged to provide the preliminary drying, the annealing and the final drying chambers in successive levels as parts of a single unitary housing or cabinet, as 6. In some factories, the ceiling height may be too low to admit of installation of the apparatus so construed, in which case the housing or cabinet may be divided into two sections as A and B schematically illustrated in Fig. 5; section A to contain the preliminary drying and annealing chamber, and section B to contain the final drying chamber; a suitable intermediate conveyer, as C, being utilized to transfer the material under treatment from the annealing chamber of section A to the final drying chamber of section B.

It will be obvious that various changes could be made in the construction of the apparatus, and that widely different embodiments of the invention, as well as variations in the steps of the processing treatment involved, could be made without departing from the scope of the invention as defined in the appended claims. It is there-

fore intended that all matter contained in the above description and shown in the accompanying drawings shall be interpreted as illustrative and not in a limiting sense.

I claim:

1. In an apparatus of the kind described, means to provide a series of superimposed segregated enclosed chambers to provide in successive order from top to bottom a preliminary drying chamber having means to circulate air therein, an intermediate chamber to contain relatively still air, and a final drying chamber having means to circulate air therein; a plurality of traveling mesh screen belts within said preliminary chamber over which the material treated is successively passed, said belts being of such number as to determine a relatively long period of submission of said material to the circulating air within said preliminary chamber; a single traveling belt within said intermediate chamber over which the material is passed for a relatively short period of submission to the still air of said intermediate chamber; a plurality of traveling mesh screen belts within said final chamber over which the material is successively passed, said belts exceeding in number those of said preliminary drying chamber so as to determine a period of submission of the material treated to the circulating air within said final chamber longer than that in said preliminary drying chamber; and means to transfer the material by gravity successively from the belt means of one chamber to that of a succeeding chamber.

2. In an apparatus of the kind described as defined in claim 1, means for charging the still air of said intermediate chamber with steam, and means to heat at will the air circulated respectively in said preliminary and final drying chambers.

3. In apparatus for the purposes described, means to provide a series of successive enclosed chambers comprising a preliminary drying chamber having means to circulate air therein, an intermediate chamber to contain relatively still air, and a final drying chamber having means to circulate air therein; a plurality of conveyer belts within said preliminary chamber over which the material treated is successively passed, said belts being of such number as to determine a relatively long period of submission of said material to the circulating air within said preliminary chamber; a single conveyer belt in said intermediate chamber over which the material is passed for a relatively short period of submission to the still air therein; a plurality of conveyer belts within said final chamber over which the material is successively passed, said belts exceeding the number of those of said preliminary drying chamber so as to determine a period of submission of the material treated to the circulating air within said final chamber longer than that in said preliminary drying chamber; and means to transfer the material successively from the belt means of one chamber to that of a succeeding chamber.

4. In apparatus for the purposes described as defined in claim 3, means for charging the still air of said intermediate chamber with steam, and means to heat at will the air circulated respectively in said preliminary and final drying chambers.

NICHOLAS J. CAVAGNARO.
